Filed Aug. 30, 1963, Ser. No. 307,763

1 Claim. (Cl. 15—528)

(1) *Title of invention, Felt Pen.*

This invention relates to a felt pen, the writing tip of which is interchangeable and may be used for writing fine to coarse or large characters or letters.

An object of the invention is to provide a felt pen having interchangeable felt or fabric tips which will not become hardened by the solidifying of the ink and which may be used for the writing of large or heavy to fine characters or letters.

Another object of the invention is to provide a felt pen in which one pen part is made of a winding of a piece of paper with the outer surface thereof coated with a setting resin and having a central opening in which is inserted a body of twisted yarn also having a setting resin on the outer surface thereof, thus forming a felt pen in which the larger cylindrical body of paper may be used in the writing and several tips formed of the twisted yarn and of varying sizes may be inserted in the central opening of the wound paper.

(2) *Brief description of drawings*

FIG. 1 shows the longitudinal section of the entire felt pen of this device, FIG. 2 shows the longitudinal section of the pen body part and FIG. 3 is the longitudinal section showing the pen body part with the fine wick removed.

(3) *Detailed description of device*

This device concerns a felt pen in which felt padding 4 with tip 3 installed protruding downward is installed inside pen body fitting tube 2 which is fitted to the tip of the ink tube 1, main pen part 6 formed by winding a piece of paper into a cylindrical form and whose outer surface has been coated with setting resin 5 is inserted and installed on said padding 4, the entire inner surface of the middle hole 7 of pen body 6 is impregnated with setting resin, and one or more fine pen body 9 of twisted yarn with setting resin layer 8 formed similarly on the outer surface is fitted freely withdrawable and insertable and 10 in the drawing shows a cover screwed in as the bottom cover at the bottom of ink tube 1.

Previously in the conventional felt pen, the entire pen body was made with a piece of felt and this was fitted into the ink tube but as the pen body is a piece of felt, only thick letters could be written and it also had the defect of preventing writing due to drying and adherence of ink on the pen body, causing scratching when writing.

This device has the characteristic of not only permitting writing fine letters which could not be written with the

2

previous pen, with the fine pen body 9 but also the fine pen body 9 can be removed or replaced as one or more fine pen body 9 of twisted yarn with setting resin layer formed on the outer surface by impregnating setting resin 5 paint on the outer surface is inserted freely withdrawable or insertable in the main pen body 6 which is formed by winding a piece of paper in cylindrical form with the entire inside of the middle hole 7 impregnated with setting resin and whose outer surface has been coated with setting plastic layer 5 to make the pen body a double wall construction.

However, as the main pen body 6 is formed by winding a piece of paper in cylindrical form and coating the outer surface with setting resin layer 5, this part can write in the same manner as the conventional pen and also, it is possible to remove solidified ink by sharpening the main pen body 6 as required during use and also to correct the deformation caused by writing.

As felt padding 4 is inserted with a tip 3 protruding downward as the padding of ink of both pen bodies 6 and 9 in the pen body fitting tube 2 in which is fitted both pen bodies 6 and 9 of double wall construction and as the tip 3 is inserted in ink tube 1, compared with the device in which the ink flows out and supplies ink simply from the passage hole of fitted tube 2, supply of ink to both pen bodies 6 and 9 is smooth, the felt padding 4 always stores ink without excess or insufficient ink to wet both pen bodies 6 and 9 appropriately and has the effect of preventing abnormal drying of the pen body surface. As pen bodies 6 and 9 are formed by rolling a piece of paper and twisted yarn and coated with setting resin, it is appropriately hard and also soft for writing when compared with a pen body of a felt piece and also, it is possible to write not only on the surface of paper but also on the surface of any object.

I claim:

A construction of felt pen in which felt padding (4) with tip (3) installed protruding downward is installed inside pen body fitting tube (2) which is fitted to the tip of ink tube (1), main pen part (6) formed by winding a piece of paper into a cylindrical form and whose outer surface except for the ends has been coated with setting resin (5) is inserted and installed on said padding (4), the entire inner surface of the middle hole (7) of pen body (6) is impregnated with setting resin, and one or more fine body (9) of twisted yarn with setting resin layer (8) formed similarly on the outer surface except for the ends is fitted freely withdrawable and insertable within said middle hole.
